ATT'YS.

UNITED STATES PATENT OFFICE.

DAVID BRICKMAN, OF LOS ANGELES, CALIFORNIA.

GAS-BURNER.

1,294,999.

Specification of Letters Patent. Patented Feb. 18, 1919.

Application filed August 29, 1918. Serial No. 251,974.

To all whom it may concern:

Be it known that I, DAVID BRICKMAN, a citizen of the United States, residing at Los Angeles, in the county of Los Angeles and State of California, have invented new and useful Improvements in Gas-Burners, of which the following is a specification.

My object is to make an improved gas burner especially adapted for bake ovens, and my invention consists of the novel features herein shown, described and claimed.

Figure 1 is a fragmentary side elevation of a bake oven showing a gas burner, embodying the principles of my invention, in position for use.

Fig. 2 is a fragmentary end elevation of the bake oven and showing the gas supply pipe and regulator valves of the burner.

Fig. 3 is an enlarged top plan view of the burner, and looking in the direction indicated by the arrow 3 in Fig. 2, parts being shown in section.

Fig. 4 is a vertical cross sectional detail on the line 4-4 in Fig. 3.

Fig. 5 is a vertical cross section on the line 5-5 in Fig. 4.

The shell 1 of the bake oven rests upon a foundation 2, and a burner opening 3 is formed in the end wall 4 of the shell 1, there being a sliding door 5 for closing the opening 3. A passage 6 is cut through the end wall 4 at one side of the opening 3 and communicating with the opening. The opening 3 is large enough to allow the burner 7 to pass through the opening and the burner pipes 8 pass through the passage 6. The pipes 8 are connected to the supply pipe 9 by union 10, there being a stop cock 11 in the pipe 9 so that the stop cock 11 may be closed, the union 10 disconnected and the burner 7 and pipes 8 removed from the bake oven for cleaning, repairing, and so on.

The burner 7 consists of the independent sections 12, 13, 14 and 15, each section having an independent feed pipe 16, 17, 18 and 19, each feed pipe being controlled by a separate regulating valve 20, 21, 22 and 23, the union 10 is connected to a pipe nipple 24, a T 25 is connected to the nipple 24, and the valve 23 is connected to the side outlet of the T 25. A second T 26 is connected to the end outlet of the T 25 and the valve 22 is connected to the side outlet of the T 26. A third T 27 is connected to the end outlet of the T 26, and the valve 21 is connected to

the side outlet of the T 27, and the elbow 28 is connected to the end outlet of the T 27, and valve 20 is connected to the other end of the elbow.

A rectangular angle iron frame 29 is mounted upon legs 30, said frame 29 being large enough to support and form a base for the four burner sections 12, 13, 14 and 15. The burner section 12 has a rectangular sheet metal casing 31 and vertical partitions 32 and 33 equally spaced apart relative to the ends of the casing. A sheet 34 of woven wire is mounted in position to form a bottom for the casing 31 and the bottom rests upon the horizontal flanges 35 and 36 of the angle iron frame 29. A sheet 37 of woven wire is stretched over the top of the casing 31 and held in place by a binding 38. The section 39 of the feed pipe 16 has gas discharge orifices 40, 41, and 42, and the section 39 is inserted transversely through the casing 31 at the bottom of the casing above the woven wire 34 and through the angle iron frame 29, and a cap 43 placed upon the dead end of the pipe section.

In a like manner, the pipe sections 44, 45 and 46, are mounted in the burner sections 13, 14 and 15.

When the valve 20, for instance, is opened, the gas will flow through the orifices 40, 41 and 42 and discharge upwardly and draw the air through the woven wire 34 and the mixture will pass upwardly through the woven wire 37 and burn on top of the woven wire 37. The woven wire 37 has considerable area, the casing 31 is of considerable height, and the discharge of the gas through the orifices stimulates a draft which will draw the fresh air through the woven wire 34 in abundance to produce a perfect mixture, and the woven wire 37 is fine enough so that the flame will not pass through the woven wire and burn back to the orifices. Each section 12, 13, 14 and 15 of the burner is substantially alike, and each section may be operated independently of the other section and each section may be finely regulated by the valves 20, 21, 22 and 23.

In actual practice, the door 5 is opened, the valve 23 opened and a flame applied above the woven wire 37 to ignite the burner section 15, then the valve 22 may be opened and the section 14 will light from the section 15 and the valve 21 may be opened and

the section 13 will light from the section 14, and finally the valve 20 may be opened and the section 12 will light from the section 13. After the sections have all been 5 ignited they may be regulated independently of each other.

Various changes may be made without departing from the spirit of my invention, as claimed.

10 I claim:

1. A gas burner comprising a rectangular angle iron frame constructed to form horizontal flanges extending inwardly from the bottoms of vertical flanges; a sheet of 15 woven wire fitting within the vertical flanges upon the horizontal flanges; a rectangular casing open at the top and bottom fitting within the vertical flanges upon the edges of the woven wire; a sheet of 20 woven wire stretched over the top of the casing and bent downwardly outside of the casing; a binding fitting around the casing outside of the downwardly extending portions of the woven wire and secured 25 to the casing to hold the woven wire in place; and a gas pipe extending through the vertical flanges and through the bottom of the casing above the bottom sheet of

woven wire and having orifices discharging upwardly.

2. A gas burner comprising a rectangular angle iron frame constructed to form horizontal flanges extending inwardly from the bottoms of vertical flanges; a sheet of woven wire fitting within the vertical 35 flanges upon the horizontal flanges; a rectangular casing open at the top and bottom fitting within the vertical flanges upon the edges of the woven wire; partitions fixed vertically in the casing to form a plurality of chambers; a second sheet of woven wire stretched over the top of the casing and bent downwardly outside of the casing; a binding fitting around the casing outside of the downwardly extending portions 40 of the woven wire and secured to the casing to hold the woven wire in place; and a gas pipe extending through the vertical flanges and through the bottom of the casing above the bottom sheet of woven 45 wire and having orifices discharging upwardly into the chambers.

In testimony whereof I have signed my name to this specification.

DAVID BRICKMAN.
